MOUNT FOR TWIN SEARCHLIGHTS

George E. Meese, East Cleveland, Ohio, assignor
to General Electric Company, a corporation of
New York

Application April 13, 1946, Serial No. 662,042

5 Claims. (Cl. 240—61.05)

1

My invention relates to searchlights and more particularly to mounts therefor. The principal object of my invention is to provide a mount having a control mechanism for a pair of searchlights by which the two projected beams may be aimed in tandem through 360° azimuthally and 20° to 30° above and below horizontal. Another object of the invention is to provide a mount having a control mechanism for a pair of searchlights by which the projected beams may be caused to diverge or converge and may be displaced in elevation with respect to each other.

Still further objects and advantages of the invention will appear from the following detailed description of species thereof and from the accompanying drawing in which Fig. 1 is a front elevational view of a searchlight unit or assembly having a control mechanism embodying my invention; Fig. 2 is a plan view of the searchlight unit shown in Fig. 1; Fig. 3 is a side elevational view of the searchlight unit; Fig. 4 is an enlarged top plan view of part of the control mechanism shown in Figs. 1, 2 and 3; Fig. 5 is a front elevational view of the mechanism shown in Fig. 4, with a part thereof broken away and shown in section; Fig. 6 is a side elevational view of the mechanism shown in Fig. 4 rotated 180 degrees from the position shown in Fig. 4 and having a part thereof broken away; and Fig. 7 is a similar view of part of the control means shown in Figs. 4 to 6 and turned 180 degrees from its position in Fig. 6.

Referring to Figs. 1, 2 and 3 of the drawing the searchlight unit comprises a pair of searchlights 1 and 2 mounted on trunnions at the ends 3, 4 and 5, 6 of the cradle arms 7, 8 and 9, 10 so that the searchlights 1 and 2 may be tilted upwardly or downwardly on a horizontal axis. The cradle arms 7, 8 and 9, 10 are pivoted as shown at 11 and 12 (Fig. 1) on a supporting frame 13 so that the searchlights 1 and 2 may be turned on vertical axes toward or away from each other. The supporting frame 13 is journaled to a vertical column or pillar 14 (Fig. 3) and may be rotated a full 360° to change the direction of the light beams projected by the searchlights. The vertical column 14 is fixed to a base 15 which may be secured to the floor of a motor truck body, the deck of a boat, or the like. A vertically adjustable seat 16 for the operator is mounted in back of the searchlights and on the supporting frame 13 in a position in which the controls for the searchlights are within easy reach of the operator. A platform 17 is also provided on the frame for the feet of the operator.

2

The frame 13 comprises lower support members 18 attached to a bearing member 19 on the column 14 (Figs. 1 and 3) and supporting the seat 16, the pivot posts 11 and 12 and therewith the searchlights 1 and 2. A pair of brace members 21 and 22 extend upward from the lower members 18 and are attached to the upper bearing 23 on the column 14 (Fig. 6). Also fastened to the upper bearing 23 is an elongated housing 24 which supports the mechanism for controlling the various movements of the searchlights 1 and 2.

The mechanism for controlling the rotation of the support frame 13 about the column 14 comprises spiral gearing including a stationary gear 25 affixed to the upper end of the column 14 (Figs. 4, 5 and 6) and a worm gear 26 affixed to a shaft 27 journaled to a clutch arm 28, the lower end of which is attached to the frame 13 by a pivot rod 29 passing through studs 30 on said frame 13. The top of the clutch arm 28 is attached to the housing 24 by a clutch throw-out handle 31 which is journaled to the clutch links 32 and the studs 33 on the clutch arm 28 and the housing 24 respectively (Figs. 4 to 6). Shifting of the clutch arm 28 from a position in which the worm gear 26 and the gear 25 are engaged (Figs. 4 to 6) to a position, shown in light broken lines in Fig. 5, in which the gears 25 and 26 are disengaged is accomplished by turning handle 31. The assembly including frame 13 and the searchlights 1 and 2 thus may be quickly rotated through a large angular distance, such as 180°, by first turning the handle 31 to disengage the gears 25 and 26 and then pushing on part of the assembly offset from the column 14. The gears 25 and 26 may be re-engaged by turning handle 31 to hold the assembly in the new position. Adjustments of the assembly in the new position may be made by turning handle 34 on shaft 27 to accurately aim the searchlight beams at the target. The gears 25 and 26 may be used to move the assembly any desired angular distance, of course.

The means for tilting the searchlights so as to change the position of the projected light beams with respect to the horizontal and the means to change the tilt of the searchlights with respect to each other to cause the projected beams to be displaced in elevation is shown in Figs. 4 to 7 and comprises a gear box 35 mounted on top of the housing 24. The gear box 35 is provided with a shaft 36 passing through a stud 37 on housing 24 and having a handle 38 within easy reach of the operator. The shaft 36 turns a worm gear which engages a sector gear inside the box 35. These gears reduce the rate of motion and the sector

gear is mounted on a drive shaft 39 (shown in dotted lines in Figs. 4 and 5 and in section in Fig. 6) which protrudes from both sides of the gear box 35. The gears in the interior of the gear box 35 have not been shown for simplicity of illustration and since these are conventional. The axles 40 of the searchlights 1 and 2 pass through the trunnions on the arms 8 and 9 and universal joints 41 and 42 are splined to the axles 40. The universal joints 41 and 42 are attached to the end portions of the drive shaft 39 and rotate therewith to tilt the searchlights about a horizontal axis and on the supporting arms 7 to 10 as the handle 38 of the shaft 36 is turned by the operator. The light beams thus may be directed up or down in tandem through the same angular distance, such as 20° to 30° above and below the horizontal, by turning the handle 38 in the proper direction.

The universal joint 41 is fixed to the shaft 39 but the joint 42 is secured to the said shaft by a pin 43 set into shaft 39 and passing through a circumferential slot 44 in the part of the universal joint engaging drive shaft 39 as shown in Figs. 4 and 5. The slot 44 is of sufficient length to allow the universal joint 42 to be rotated approximately 60 degrees with respect to the shaft 39 to change the position of the searchlight 2 with respect to that of the searchlight 1. The projected light beams thus may be displaced vertically with respect to each other by changing the relative positions of the universal joints 41 and 42 on the drive shaft 39.

The means for changing the relative positions of the joints 41 and 42 comprises a pair of lever arms 45 and 46 which are fixed to the shaft 39 and the universal joint 42, respectively. The free ends of arms 45 and 46 are provided with pivoted collars 47 and 48, respectively, which engage a threaded shaft 49 provided with a handle 51. Rotating the handle 51 causes relative displacement of the free ends of the arms 45 and 46 and thus relative rotary displacement of the universal joint 42 and the shaft 39. When the desired relative tilt of the searchlights 1 and 2 has been attained by turning the handle 51 the handle 38 may be turned to elevate or depress the projected light beams simultaneously.

The gear box 35 is held on the housing 24 by a pair of guide rails 53 and 54 fixed to the housing 24 and engaging the base-plate 55 of the gear box as shown in Figs. 4 and 5. The gear box 35 is provided with a dog 56 which engages a threaded shaft 57 (Figs. 5 and 6) journaled to the front and back of the housing 24 and which may be turned by the shaft 58 provided with the handle 59 to move the gear box 35 along the housing 24. The movement of the gear box 35 is transmitted through the universal joints 41 and 42, which are splined to the axles 40, to turn the searchlights 1 and 2 on the pivots 11 and 12. Thus, by turning handle 59, which is shown in Fig. 6 turned about 90° from the position shown in Fig. 4, the searchlights may be turned to toe in or out and to cause the projected light beams to diverge or converge.

What I claim as new and desire to secure by Letters Patent of the United States is:

1. In a searchlight assembly, the combination of a vertical column, a frame mounted to rotate on said column, a pair of searchlights having axles extending horizontally therefrom, means supporting said searchlights on opposite sides of said column through their said axles and mounted on said frame for rotation on vertical axes, and

coupling means for said searchlights carried by said frame and including universal joints connected to the searchlight axles, one of said joints being arranged for rotary displacement with respect to one of said axles whereby the searchlights are tiltable at different angles, and including also means engaging said joints for rotating the searchlight axles in the same direction about their axes to tilt the projected light beams above or below the horizontal and means connected to said joints and arranged to cause rotation of the searchlight supporting means in opposite directions about their vertical axes to toe the searchlights in or out.

2. In a searchlight assembly, the combination of a vertical column, a frame mounted to rotate on said column, a pair of searchlights having axles extending horizontally therefrom, means supporting said searchlights on opposite sides of said column through their said axles and mounted on said frame for rotation on vertical axes, and coupling means for said searchlights carried by said frame and including universal joints connected to the searchlight axles, one of said joints being arranged for rotary displacement with respect to one of said axles whereby the searchlights are tiltable at different angles, and including also means engaging said joints for rotating the searchlight axles in the same direction about their axes to tilt the projected light beams above or below the horizontal, means for rotating the axles of the respective searchlights in opposite directions about their axes to displace the light beams in elevation with respect to each other and means connected to said joints and arranged to cause rotation of the searchlight supporting means in opposite directions about their vertical axes to toe the searchlights in or out.

3. In a searchlight assembly, the combination of a vertical column, a frame mounted to rotate on said column, drive means on said frame and engageable with said column for rotating said frame about said column, a pair of searchlights having axles extending horizontally therefrom, means supporting said searchlights on opposite sides of said column through their said axles and mounted on said frame for rotation on vertical axes, and coupling means for said searchlights carried by said frame and including universal joints connected to the searchlight axles, one of said joints being arranged for rotary displacement with respect to one of said axles whereby the searchlights are tiltable at different angles, and including also means engaging said joints for rotating the searchlight axles in the same direction about their axes to tilt the projected light beams above or below the horizontal and means connected to said joints and arranged to cause rotation of the searchlight supporting means in opposite directions about their vertical axes to toe the searchlights in or out.

4. In a searchlight assembly, the combination of a vertical column, a frame mounted to rotate on said column, drive means on said frame and engageable with said column for rotating said frame about said column and clutch means on said frame for moving said drive means into and out of engagement with said column, a pair of searchlights having axles extending horizontally therefrom, means supporting said searchlights on opposite sides of said column through their said axles and mounted on said frame for rotation on vertical axes, and coupling means for said searchlights carried by said frame and including universal joints connected to the searchlight axles, one

of said joints being arranged for rotary displacement with respect to one of said axles whereby the searchlights are tiltable at different angles, and including also means engaging said joints for rotating the searchlight axles in the same direction about their axes to tilt the projected light beams above or below the horizontal and means connected to said joints and arranged to cause rotation of the searchlight supporting means in opposite directions about their vertical axes to toe the searchlights in or out.

5. In a searchlight assembly, the combination of a vertical column, a frame mounted to rotate on said column, a pair of searchlights having axles extending horizontally therefrom, means supporting said searchlights on opposite sides of said column through their said axles and mounted on said frame for rotation on vertical axes, and coupling means for said searchlights carried by said frame and including universal joints engaging the searchlight axles, one of said joints being

arranged for relative rotary displacement with respect to the other whereby the respective searchlights are tiltable at different angles, and drive means engaging said joints for rotating the searchlight axles in the same direction about their axes to tilt the projected light beams above or below the horizontal and to cause rotation of the searchlight supporting means in opposite directions about their vertical axes to toe the searchlights in or out.

GEORGE E. MEESE.
